ANALYTICAL METHOD

Casimir J. Munter, Upper St. Clair Township, Allegheny County, Pa., assignor to Hagan Chemicals & Controls, Inc., a corporation of Pennsylvania

No Drawing. Filed July 25, 1958, Ser. No. 750,896

5 Claims. (Cl. 23—230)

The present invention relates to a rapid and effective method of analyzing steam or water samples to ascertain with accuracy the presence of certain aliphatic amines.

In recent years certain high molecular weight amines and their salts, often simply called "filming amines," have been used extensively to protect the surfaces of pipes and fluid-conveying apparatus in contact with aqueous solutions which are corrosive to metals. This corrosive action is generally caused by carbon dioxide, oxygen, ammonia, or other substances in either a gaseous, vapor, or liquid state, present in the water or steam being transported in the pipes.

The principal application of the amine compounds is in steam generating apparatus. The compounds may be added either to the boiler water where during the conversion of the water to steam, a certain portion of the amine compound is carried over with the steam into the pipes and other conduits which carry the steam to the point of use, or they may be added directly to the steam line by suitable chemical feeding equipment. The addition of the high molecular weight amines and related compounds to the steam line of a system is described in U.S. Patent 2,460,259 which issued to Harry Lewis Kahler, while the addition of these compounds to boiler waters is described in U.S. Patent 2,400,543 which issued to Wayne L. Denman. This second patent was subsequently reissued as Re. 23,614 and re-issued as Re. 24,473.

The amine compounds which are disclosed in these patents for preventing corrosion in steam systems apparently form a mono-molecular film on metal surfaces. This film protects iron, steel, brass, copper and other metals from corrosion. The amount of corrosion-inhibiting amine compound initially added to either the steam or the boiler is very small, usually in the range of from 1 to 10 parts per million, based on either the steam or boiler water, depending upon the point of introducing the inhibitor. Although larger or smaller amounts may be used, the amine compounds are relatively costly and obviously it is desirable to minimize the concentration for economical operation of the system. Since the amine forms a thin film on the metal surfaces throughout the system, the ultimate amount detectable will be small and a safe working range after the system is properly treated will be from $\frac{1}{8}$ to $2\frac{1}{2}$ p.p.m.

Accurate control of the amount of amine is highly desirable, and to this end, a number of tests have been proposed by workers in the art but none has proven satisfactory largely because of the very low concentration of amine that is detectable in most instances. Most of the amine compounds used are water-insoluble and any titration method for determining amine in the steam system involves extraction of the amines from the boiler water and/or condensed steam by organic solvents followed by further analytical procedure. This can lead to appreciable error particularly in the extraction phases of the procedure.

2

I have found that the high molecular weight amines, and amine salts which are used in practicing the inventions claimed in the Denman and Kahler patents may be detected even in very minute amounts by observing a color change produced on a metal-dye lake formed in a buffered solution. The color ranges from a golden yellow with no amine compound present through various gradations of green to a deep blue where 2.5 parts per million of the amine compound are detected.

10 I have found that my method may be applied to a process using a lake of copper and Azurol B dye in conjunction with a colorimeter for estimating the amount of amine present. Other metal-dye lakes such as zinc may be used in this method but the combination of the Azurol B dye and copper is by far the most satisfactory.

Reagents

Before carrying out my test procedure, I prepared three reagents which I call No. 1, No. 2, and No. 3. 20 They are compounded as follows:

No. 1. 216 ml. of reagent-grade glacial acetic acid (99.5%) are added to about 600 ml. of distilled water in a one liter volumetric flask. The solution is diluted to the one liter mark with distilled water and the flask 25 is agitated to insure complete mixing.

No. 2. A stock solution of the dye is prepared by dissolving 14 grams of reagent-grade sodium carbonate and 14 grams of reagent-grade sodium bicarbonate in about 400 ml. distilled water in a 500 ml. volumetric flask.

30 After the carbonates are thoroughly dissolved, 2.580 grams of Chromoxane pure Blue BA New CF dye are added to the solution. This dye is commonly known as azure blue or Azurol B dye. The flask is stoppered and agitated until the dye is completely dissolved. The

35 solution is then diluted to the 500 ml. mark with distilled water. To convert the stock solution of the dye into the dilute solution employed in the test, 28 grams of reagent-grade sodium carbonate and 28 grams of reagent-grade sodium bicarbonate are completely dissolved in about 700 ml. of distilled water in a one liter volumetric flask and exactly 10 ml. of the stock dye solution which has already been prepared is added to the flask and it is further diluted to the one liter mark with distilled water. Reagent No. 2 is now ready for use.

40 No. 3. A stock solution of this reagent is first prepared by adding exactly 1.150 grams of reagent grade cupric sulfate ($CuSO_4 \cdot 5H_2O$) and 15.6 ml. of reagent-grade glacial acetic acid (99.5% CH_3COOH) to about 700 ml. of distilled water in a one liter volumetric flask.

45 The flask is agitated until the solids are completely dissolved and the solution is then diluted to the one liter mark with distilled water. The final reagent is then prepared by further diluting exactly 100 ml. of the prepared stock solution to one liter with distilled water.

Sampling

Having prepared the reagents, the sampling technique is carried out as follows:

50 (1) I add by means of a graduated cylinder 10 ml. of reagent No. 1 to a clean 500 ml. Pyrex glass sampling bottle.

55 (2) The sampling bottle is then filled to the bottom of its neck with the sample to be analyzed. The bottle is capped and shaken to obtain uniformity of contents. If the sample is hot it should be cooled in the bottle or about 75 ml. of the sample should be withdrawn, and this portion should be cooled in an Erlenmeyer flask to 90° F. or less.

60 (3) If the sample to be analyzed is turbid or contains organic coloring matter, 200 to 300 ml. of the sample

should be collected in a separate container for reference purposes. Reagents are not added to this sample.

Analysis

To carry out the actual analytical procedure which is the subject of my invention, I perform the following steps:

(1) 500 ml. of the cool acidified sample suspected of containing from 0 to 2.5 p.p.m. of amine compound are placed in an Erlenmeyer flask.

(2) From a graduated cylinder 10.0 ml. of reagent No. 2 are added to the Erlenmeyer flask and the flask is swirled gently for mixing purposes.

(3) From a graduated cylinder 10.0 ml. of reagent No. 3 are added and mixed gently.

(4) A conventional viewer containing three viewer tubes is placed in position so that the tops of the tubes point toward a window or other source of light. The outer two tubes are filled to their respective marks with clear tap water or with an actual blank sample if the sample is turbid or contains organic coloring matter. After solution from step 3 has been allowed to stand 20 minutes, the center tube is filled to the mark with this solution. A color slide is placed in the slots so that one of the arrows on the slide is directly below the white arrow on the name plate of the viewer. The sample under observation is compared with the color standards by looking at the reflections of the three tubes in the mirror rather than by looking down through the tubes. If the color of the sample does not match either of the standards or does not lie between them, the slide is moved until the next arrow is below the mark on the viewer and the comparison is again made. The amine concentration in parts per million is read from the value of the matching standard.

In carrying out my procedure, I prefer to use a viewer sold by Hagan Chemicals & Controls, Inc. known as a Hagan Viewer No. 150 because the analytical procedure using a viewer is extremely accurate and is preferred where precise determinations are to be made. However, it is possible to eliminate the fourth step, viz, the use of the viewer, and make a visual observation at the conclusion of the third step in the flask or in standard colorimetric tubes. If the sample being observed has a golden yellow color, no filming amine is present. If a deep blue color develops, the analyst will know that 2.5 p.p.m. or more of amine is present and the concentration in the boiler or the steam line can safely be reduced for economical operation. In other words, assuming that a desirable concentration of amine compound is one part per million, accurate control can be maintained by making periodic analyses and holding the amine dosage to such a level that a greenish color will develop in the sample at step 3 in the procedure outlined above. I have found that as little as one-eighth part per million of the amine compound can be detected effectively by my procedure.

In the prevention of corrosion in steam generating apparatus, other amino compounds such as ammonia, morpholine and cyclohexylamine are used. These are not "filming" amines. It is interesting to note that my method of analysis when the copper lake is used is completely insensitive to ammonia, morpholine, and cyclohexylamine, but is extremely sensitive to the so-called long-chain amines such as octadecylamine ($C_{18}H_{37}NH_2$), or any of the compounds used in the methods disclosed in the Denman and Kahler patents. Broadly speaking, these compounds are generally represented by the formula:

In this formula, R denotes an alkyl group; R' and R'' represent hydrogen or an alkyl group. This formula is intended to cover the primary, secondary, and tertiary amines. When one hydrogen is replaced in NH_3 , the resulting compound may be designated RNH_2 . When

two hydrogens are replaced, the secondary amine is represented by $RR'NH$ and contains an imino group; and when three hydrogens are replaced, the tertiary amine is formed having the formula $RR'R''N$.

5 It is well known in the art that many dyestuffs will combine with metal ions to form insoluble compounds known as lakes. The rate of precipitation or flocculation of these compounds varies considerably, although in due time the insoluble form generally comes out of

10 solution.

It has been found that some combination of dyes and metal ions newly formed or formed in the presence of a stabilizing agent will not precipitate or flocculate immediately. One such dye is Eriochrome Azurol B

15 (CI-720). Its magnesium salt can be formed without immediate precipitation and can be stabilized for long periods with polyvinyl alcohol. (Hart, J. A. and Lee, E. W., Tappi, vol. 34, No. 2, pages 77-79, February 1951.) This stabilized or newly formed lake responds

20 by a color change to additions of cationic soaps, particularly of the quaternary amine type. This combination is not responsive to long chain primary amines (filming amines) nor to other types of nitrogen compounds extensively used for corrosion control in steam and condensate systems.

By substituting other metals such as copper or zinc, for the magnesium, I have found that a stable combination of dye and metal can be made with a clear yellow or amber color and that under the proper conditions of pH value, the lake color is markedly changed by the presence of very small amounts of long chain primary amine. The pH value of the test solution after all additions have been made should be between about 6.9 and about 7.2 to achieve these results. The amounts of amine detectable can be as small as one-tenth parts per million. Short chain amines and related nitrogen compounds do not give this color change. This permits a distinction to be made among the materials commonly used for steam and condensate line corrosion problems.

35 The action of the long chain amines in producing the color change lies largely in their effect on the state of aggregation of the dyestuff, which in the case of the copper salt seems to be one of true solution, or a lake stabilized by excess dyestuff. This change in aggregation can be seen from the fact that the test solutions after the color change will flocculate in due time. Low concentrations may remain stable for days, but test solutions containing about one milligram of amine will flocculate in 24 hours.

40 50 If desired this flocculation can be prevented by the use of dispersing or stabilizing agents such as polyvinyl alcohol, acrylic acid polymers, etc. but for most purposes in carrying out my test procedures these agents are unnecessary.

55 55 Since at a concentration of 2.5 parts per million of amine in the sample being analyzed will produce a maximum depth of blue color, if it is suspected that the concentration exceeds 2.5 parts per million, the sample can be diluted with distilled water known to be free from the amine and the analysis is then made on the diluted sample.

60 65 Although in the foregoing procedure I have outlined a preferred method of preparing reagents which involves a rather exacting method and precise amounts of specific reagents, it should be pointed out that the principal objective is to prepare the three reagents in such a manner that the final pH value of the sample undergoing analysis is in the working range of about 6.9 to 7.2. Hence reagent No. 1 is merely an acidic solution which when combined with the alkaline reagent No. 2 yields the proper pH value. Glacial acetic acid is prepared in reagent No. 1 but of course any mineral acid such as hydrochloric, sulfuric, nitric, or phosphoric acid could be used instead. However, the acetic acid is much more

amenable to buffering with the alkaline salts than are the mineral acids. With the latter, control of the pH is difficult.

While I have mentioned two brands of azure blue dye (Azurol B in textile circles) there are other brands which are equally satisfactory. The designation "CI-720" is the official color index designation of the dye.

Azurol B is chemically the condensation product of orthocresotinic acid and orthodichlorobenzaldehyde.

I claim:

1. A method of determining the presence of long-chain primary, secondary, and tertiary aliphatic amines in aqueous media which comprises forming a lake of copper and Azurol B dye, adjusting the pH value of the lake to between about 6.9 and 7.2, adding thereto an aqueous media containing a long-chain aliphatic amine and observing the color of the lake.

2. A method of visually determining the concentration in aqueous media of long-chain primary, secondary, and tertiary aliphatic filming amines, which comprises adding to a measured quantity of the aqueous media a buffered solution of a lake of copper and Azurol B dye, maintaining the pH value of the resultant solution in the range of from about 6.9 to about 7.2 and thereafter colorimetrically determining the concentration of amine.

3. A method of determining the presence of long-chain primary, secondary, and tertiary filming aliphatic amines containing at least eleven carbon atoms in an alkyl radical thereof which comprises reacting a buffered

solution of copper and Azurol B dye at a pH of from about 6.9 to about 7.2 with a dilute solution containing less than 10 parts per million of said amine, and thereafter colorimetrically determining the concentration of amine by comparison with known color standards.

4. A method of determining the presence of a filming amine of the long-chain aliphatic type in aqueous media which comprises forming a lake of copper and Azurol B (CI-720) in an aqueous solution buffered to a pH value of from 6.9 to 7.2 whereby upon visual inspection the lake will range in color from amber yellow with no amine present through green to a deep blue with 2.5 parts per million of amine present.

5. A method of determining the presence of long-chain aliphatic amines in aqueous media without interference from other types of amines present which comprises forming a lake of copper and Azurol B dye in the presence of an aqueous sample suspected of containing a long-chain aliphatic amine and observing the color of the lake.
